ANIMATED DISPLAY AQUARIUMS

Adam M. Markowski, Philadelphia, Pa.

Application January 22, 1953, Serial No. 332,709

20 Claims. (Cl. 119—5)

My invention relates to display devices, and it relates 15 more particularly to displays of the action type as well as those involving miniature representations and live subjects.

One object of my invention is to provide a portable display which is relatively inexpensive to construct, of 20 unique interest, and which will have universal appeal.

Another object of my invention is to provide a substantially unitary display device which is capable of being used in a variety of manners, each with its own appeal, and which may be used in conjunction with auxiliary devices such for instance as a Christmas tree, to form a blending base therefor.

A further object of my invention is to provide a display device which combines growing or otherwise live subjects with mechanical construction and operation to form a unitary, eye-catching and attention-holding display.

Another object of my invention is to provide a display device adapted to hold live subjects, such for instance as fish, and which is so constructed as to encourage eye-appealing movement on the part of the fish while improving the health thereof.

Further objects of my invention will appear from the description which follows hereinafter.

For the purpose of illustrating my invention, I have shown in the accompanying drawings forms thereof which are at present preferred by me, since the same have been found in practice to give satisfactory and reliable results, although it is to be understood that the various instrumentalities of which my invention consists can be variously arranged and organized, and that my invention is not limited to the precise arrangements and organizations of the instrumentalities as herein shown and described.

Referring to the drawings in which like reference characters indicate like parts:

Figure 1 represents a perspective view of a display device embodying my invention.

Figure 2 represents a plan view of a display device embodying my invention.

Figure 3 represents a sectional view taken generally along the lines 3—3 of Figure 2.

Figure 4 represents an enlarged sectional view taken generally along the lines 4—4 of Figure 2.

Figure 5 represents an enlarged sectional view taken generally along the lines 5—5 of Figure 2.

Figure 6 represents an enlarged sectional view of a miniature representation of a path, taken generally along the lines 6—6 of Figure 2.

Figure 7 represents an enlarged fragmentary view of a portion of the channel, showing one form of water-wheel and guard assembly, and embodying my invention.

Figure 8 represents an enlarged perspective view of a channel portion, showing a method of cleaning the water contained therein, which method is rendered possible by my invention.

Figure 9 represents a perspective view showing a modi-

2

fication of my display device wherein a severed tree is supported thereby and plantings combined therewith in a unitary display.

Figure 10 represents an enlarged fragmentary view of an anchor means on said display device for securing a severed tree therewith.

Figure 11 represents an enlarged, fragmentary sectional view illustrating a trunk-mounting means which may be utilized in the assembly illustrated in Figure 9.

Figure 12 represents a perspective view of a display device of modified construction, and embodying my invention.

Figure 13 represents an enlarged perspective view of the bracket, post, horizontal water-wheel and display mechanism assembly detail of a portion of the modification of my invention illustrated in Figure 12.

Figure 14 represents an enlarged, fragmentary elevational view of the assembly illustrated in Figure 13, and showing the same in relation to the propeller.

Figure 15 represents a further enlarged, vertical sectional view, taken generally along the lines 15—15 of Figure 14.

Figure 16 represents an enlarged sectional view taken generally along the lines 16—16 in Figure 13.

According to my invention I preferably provide a tray 20 having side walls 21 and 22, end walls 23 and 24, and a bottom 25. A channel 26 is preferably mounted on said bottom 25, and is preferably substantially disposed within the confines of said side walls 21, 22, and end walls 23, 24. The channel 26 comprises an inner wall 27 and an outer wall 28 spaced therefrom. The inner wall 27 and outer wall 28 are preferably each continuous and extend upwardly from the vicinity of the bottom 25 to substantially the level of the upper rim 29 of the tray walls 21, 22, 23 and 24. The channel 26 may have its own bottom (not shown), or its bottom may consist of that portion of the bottom 25 which is disposed between the walls 27 and 28. In either event the walls and bottom of the channel 26 are preferably disposed in substantially watertight relation to the rest of the tray 20. Because of its continuous nature, the wall 27 encloses a region which may hereinafter be referred to as the "island" region 30; and for purposes of comparison that portion of the tray which extends beyond the outer channel wall 28, may hereinafter be referred to as the "land" region 31.

A drainage system is preferably disposed beneath the bottom 25, and preferably comprises a plurality of drainage lines. Thus, a drainage line 32 extends beneath the bottom 25 and is in hydraulic communication with a drainage outlet 33 disposed along the bottom of one end portion of the land region 31, a drainage outlet 34 disposed along the bottom of the island region 30, and a drainage outlet 35 disposed along the bottom of another end portion of the land region 31. A suitable cock or drain valve 36 may be disposed at one end of the drainage line 32 to permit the drawing off of liquid which seeps into the line 32 from the outlets 33, 34 and 35. Another drainage line 37 is preferably disposed along the bottom 25 and extends from a drain outlet 38 disposed along the bottom portion 39 of the channel 26, to a suitable cock or other drainage valve 40 which is adapted to draw off the liquid contents of the channel 26.

A watertight jacket or tube 41 may be disposed in the land region 31 and opens at one end thereof into the channel 26. The other end thereof may open in the vicinity of a wall such as the end wall 24. The jacket 41 is preferably disposed in watertight relation to the interior of the land region 31, and extends through the outer channel wall 28 in preferably watertight relation thereto. A propeller shaft 42 is rotatably mounted within the tube 41 and preferably extends throughout the

length of the tube 41 and beyond the inner and outer ends thereof. A propeller 43 is fixedly mounted on the propeller shaft 42 at the channel end thereof, and transmission means such for instance as the pulley 44 is preferably fixedly mounted on the outer end of the propeller shaft 42. The propeller shaft is preferably so disposed with relation to the channel 26, that the axis of rotation of the propeller 43 is inclined upwardly and in a manner to intercept the channel wall at a horizontal acute angle therewith. Thus, rotation of the propeller 43 will draw water therethrough, in an upwardly inclined direction, and in a manner to impel said water against a wall of the channel 26 operatively to cause said water to be deflected by said wall. Suitable guard means such for instance as the cage 45 is disposed about the propeller 43 and the channel end of the propeller shaft 42, operably concurrently to protect objects carried by water which may be disposed within the channel 26 from contact with the propeller 43, and to dispose turbulence-creating obstructions within the path of said water as it is being drawn into and through the propeller 43. Suitable drive means such for instance as the electric motor 46 may be mounted on the tray 20 and in drive-transmitting relation to the pulley 44 by any suitable means such for instance as the belt 47. Thus, when the motor 46 is actuated, and liquid such as water 48 is disposed within the channel 26, the propeller 43 is rotated in a manner to draw the water 48 through the cage 45 and upwardly against the channel wall 28. Thus, turbulent current is created which is guided upwardly and tangentially away from the wall 28 operably to cause surface turbulence 49 in the region of the water 48 adjacent that portion of the wall 28 which is in the path of the current 50 which leaves the propeller 43. It will be noted that this turbulence is occasioned not merely by obstructions to the current 51 leading to the propeller occasioned by the disposal of the cage 45 within the path of said current 51, but also by the disposition of portions of the cage 45 behind the propeller 43 and in the path of the current 50. The resultant highly turbulent surface 49 aspirates into the water 48 sufficient quantity of air to keep the water 48 from becoming stagnant, and in fact to maintain it in constantly fresh condition while at the same time imparting a flow of current which is relatively coaxial with the axis of the continuous channel 26.

A conduit 52 may extend upwardly through one of the regions of the tray, and is illustrated in the figures as extending through the island region 30. The conduit is preferably mounted on the tray 20 to open at one end, on the exterior of the tray 20, and at its other end to open preferably into a portion of the tray which is within the confines of its walls 21, 22, 23 and 24. Thus, the conduit 52 may open through the bottom 25, and may extend upwardly to substantially the level of the upper rim 29. The lower end 53 of the conduit 52 is preferably secured in watertight relation to the bottom 25. A hollow post 54 may be provided with an internal diameter substantially equal to the external diameter of the conduit 52, and also may have substantially fixedly disposed therein and projecting downwardly therefrom, an anchor rod 55. The upper portion of the post 54 may have mounted thereon a suitable lighting system 56. Electric wires 57 may extend from the electric lighting system 56 downwardly through the hollow interior of the post 54 and through the conduit 52 to a suitable location beneath the bottom 25 of the tray 20. The anchor rod 55 is of such width with respect to the wires 57, that it is disposable with said wires within the conduit 52 in a manner to bear against the interior of the conduit 52 a substantial distance beneath the upper edge thereof, operably to maintain the post 54 in substantial co-alignment with the conduit 52. The wires 57 may be removably connected to a suitable outlet plug 58.

A trunk mounting means such for instance as the spike 59 may be mounted on the bottom 25 in a manner to dis-

perse the downward thrust of a severed trunk 60 which may be supported thereby. Thus, for instance, the spike 59 may have a head 61 of substantially larger diameter, and secured to the bottom 25. Moreover, when legs 62 are provided for mounting the tray with its bottom 25 disposed above the floor or platform (not shown) on which the tray is to be placed, an auxiliary leg 63 may be disposed on the bottom 25 and beneath that portion thereof which is positioned immediately beneath the spike 59. Anchor members such as suitable hooks 64 may be secured to the corners where the side walls 21 and 22 respectively join the end walls 23 and 24, and in the vicinity of the upper rim 29 thereof.

A rotatable ornamental float device 65 may be provided for disposal in the channel 26, and preferably comprises a buoyant body portion 66 having weights 67 carried by its bottom portion, laterally projecting arms 68 disposed about its outer periphery, and a suitable ornamental device such for instance as the miniature representation 69 of a musician may be disposed on the upward portion of the buoyant body 65.

A vertical water-wheel 70 may be provided within the channel 26 and preferably comprises suitable vanes 71 mounted on a horizontal pivot 72, which in turn is supported by a bracket 73 which is mounted on a suitable portion of the tray assembly. Thus, for instance, the bracket 73 is illustrated as being trifurcated with its tines extending downwardly and offset with the center tine disposed substantially along a plane parallel to but spaced from the plane of the end tines. Thus the resultant bifurcated end 74 of the bracket 73 may be slipped over the upper edge of one of the channel walls 27, 28 with the pivot 72 extending over the channel 26. The bracket may thus come to rest in the vicinity of the junction of the tines 75 of the bifurcated end 74, and be supported against tilting by the faces of the tines 75 thereof bearing against the wall on which the bracket 73 is mounted.

A suitable guard means such for instance as the wire rail 76 is preferably mounted on the same wall 27 or 28 on which the water-wheel 70 is disposed, and extends into the channel 26 and about the water-wheel 70. The ends 77 of the guard rail 76 may be upwardly bent and then reversely bent at their termini so as to grip the upper edge 78 of the wall on which the rail 76 is mounted, and to dispose the main body 79 of the rail below said upper edge 78 a sufficient distance to place the main body 79 within the vicinity of the level 80 to which the water 48 is intended to be carried within the channel 26. The water-wheel 70 is of such a width, that it may be embraced by the guard rail 76 within the channel 26 and still leave room between the guard rail 76 and the opposing wall of the channel 26 for an ornamental float 65 to freely pass therebetween.

The island portion 30 and land portion 31 are preferably substantially filled with any desired soil-like material 81 such for instance as sand, gravel, peat moss, humus, or the like. Suitable vegetation 88 such for instance as moss, grass, small growing plants, flowers, cactus, or the like, may be planted in or on the soil-like material 81. If desired, miniature representations of larger objects may be disposed on the land and island regions. Thus, for instance, a pebble path 82 may be laid about the land portion, and may lead to a suitable miniature bridge 83 which spans the channel 26 between the land region 31 and island region 30, and a suitable tunnel or other ornamental structure 84 may extend over the path 82. To aid in transporting the display device without undue disturbance of its component parts, the pebble path 82 may be formed of a pliant base 85 which may be formed of a woven tape, plastic or the like, and miniature colored bits of glass, plastic, stone or the like 86 secured to the upper face of the base 85 by any suitable means such as the adhesive 87. The pliant base 85 enables the path to be snugly laid on the uneven surface of the soil 81 and vegetation 88, in a manner to resist dislodgment

therefrom, while the adhesive 87 holds the pebbles 86 against dislodgment with respect to the base 85.

In a preferred form of my invention live fish 89 are disposed in the water 48 and are preferably of a width substantially greater than that of the openings through the cage 45.

In Figures 12 to 16, inclusive, are illustrated modified constructions embodying my invention.

Thus, in Figure 12, there is illustrated parallel vertical water-wheels 95 and 96 disposed in the channel 26 in portions thereof wherein the flow of the current 94, while being continuous within the channel 26, is in opposite directions with respect to the side walls 21 and 22 of the tray 20. The vertical water-wheels 95 and 96 are preferably of similar construction and mounting, and may be constructed and mounted in the same manner as is described above for the water-wheel 70. In operation, the water-wheels 95 and 96 will each be impelled into rotation, and maintained in constant rotation, by the current 94. While the water-wheels 95 and 96 will rotate in tandem so far as the current 94 is concerned, they will in fact rotate in opposite directions with respect to the land and island regions 31, 30, and the side walls 21 and 22 of the tray 20, thereby giving the illusion of a constant relation of equal but opposite motion, without the use of gears or similar drive mechanisms to effect such motions.

Disposed in the same channel 26, in Figure 12, is illustrated a bracket and post assembly wherein motion is derived from the current 94 for operating a display device such as the aerial rotor 113 carrying suspension devices 98, while at the same time serving to draw the water 48 upwardly into a greater aeration surface 99.

This bracket and post assembly 100 comprises a bracket 101 mounted on a suitable mounting such for instance as the fork 102 secured to the upper edge of the wall 28 against which the turbulent current 50 is impinged by means of the propeller 43. An arm 103 extends preferably horizontally from the fork 102 and over the channel 26. In one preferred construction, the bracket 101 is formed of a continuous strip of sheet metal wherein one end 104 comprises the inner tine of the fork 102, and extends upwardly a suitable distance above the fork 102, whereupon it is reversely bent as at 105 and extends downwardly toward the base region of the fork 102, whereupon it extends horizontally to form the arm 103, and then extends upwardly to form the stud 106, and then rearwardly to form the platform 107 resting on the reverse fold 105, whereupon it extends downwardly to form the outside tine of the fork 102. A suitable sheet metal collar 108 may embrace the portions of the sheet metal strip extending between the outer edges of the arm 103 and platform 107 and above the fork 102. The arm 103 is disposed a substantial distance above the level 109 which is normally attained by the surface turbulence 49, but is preferably disposed not substantially higher than the upper rim 29 of the wall 28.

A suitable vertical post or shaft 110 is suitably journaled in the arm 103 and platform 107 for rotation therein. A suitable horizontal water-wheel 111 may be mounted at the lower end region of the shaft or post 110 operably to impart rotation thereto when the turbulent current 50 impinges against said water-wheel 111. The shaft 110 may extend upwardly a suitable distance and be fixedly secured in the vicinity of its upper end 112 to any desired display device, such for instance as the aerial rotor 113 which carries suspension members 98 secured to the outer ends 114 thereof by suitable flexible means such as cords or wires 115. The suspension members 98 may each comprise a weight 116 mounted on the flexible member 115, and embraced by a suitable covering 117 which is carried thereby and which may be in the shape of any desired object or other ornament. The rotor 113 may be carried by a suitable column 118 through which the shaft 112 passes, and if desired the column

118 may be fixedly secured to the shaft 112. The base 119 of the column may rest on a suitable step bearing such for instance as the washer 120. Rotation of the rotor 113 carries with it the weighted members 98, which in turn are swung outwardly by centrifugal force, thereby delineating a pattern of a transparent annulus through which the members 98 travel, the annulus being greater in diameter than the diameter formed by the outer edges of the blades 114.

In operation, the turbulent current 50 impelled by the rotation of the propeller 43 impinges against the submerged portion 121 of the post 110, and is guided upwardly therewith until it strikes the lower face 122 of the arm 103. In addition, the turbulent current 50 and the turbulent surface 49 upwardly impinge against the forward edge 123 of the inner tine 104 of the fork 102, and is guided upwardly therewith to said lower face 122. The water thus guided upwardly against the outer and inner regions of the lower face 122 of the arm 103 is drawn by capillary attraction until it completely covers said face 122 between the outer and inner regions thereof, thereby establishing a substantially vertical sheet 99 of flowing water which is being continuously fed by the turbulent current 50. Moreover, the horizontal water-wheel 111 serves to provide a brake or baffles to resist the turbulent current 50 and further to guide it upwardly, thereby further feeding the vertical sheet of water 99. In this manner, the aeration of the water 48 in the channel 26 is greatly enhanced, particularly since the primary flow is that which is engendered by the propeller 43 and is thus drawn into the turbulent stream 50 and upwardly toward the aerating sheet 99. It will thus be seen that by the same novel construction, aeration and attractive display motion are simultaneously achieved.

35 It will be obvious that my novel display device is capable of use in various manners, and affords attention-drawing and eye-appealing effects whichever manner is chosen. Thus, in one of its simplest forms, the device may be used as a purely miniature landscape scene with vegetation growing on both the "land" and "island" regions, with the channel disposed therebetween, and miniature representations 83, 84 of objects normally associated with such a landscape disposed in appropriate places about the tray. By the addition of water 48, the scene becomes more realistic, and with the addition of fish 89 it becomes even more so. With the inclusion of the waterwheel 70, or the waterwheels 98, 96, or the aerial rotor 113, the scene becomes even more picturesque; and with the operation of the propeller 43, new and startling results are brought about. Although the waterwheels and rotor thereby become actuated, the effect on the live fish is even more pronounced. The stirring of a current produces an almost electric effect on them, and no matter what position they may hitherto have been in, they tend at once to swim about and then to align themselves with the direction of the current, by swimming actively against it. Indeed, the fish are forced to swim against the flow of water in order to remain still with respect to the channel. If they do not swim against the current, they are bodily carried with it. Thus, the fish are constantly giving a display of motion which is eye-appealing and attention-drawing. Whether they swim or not, movement is displayed in the water.

With the inclusion of the ornamental floats 65, new and startling effects are added to combine with the motions already produced. Thus, the float 65 is carried by the current and in an upright condition through the channel 26. While it is moving longitudinally through the channel, momentum is engendered by its weight, and it is hurled against one of the sides 27, 28 as the channel 26 curves through its circuitous route in its closed circuit. As the float 65 is hurled tangentially against one of the side walls 27, 28 it strikes said wall with one of its lateral projections 68. In so doing, the projection 68 tends to be retained by said wall while the current carries the

body portion 66 forward, thereby imparting a spin to the body portion 66. The ornamental float 65 is then carried along with the current while it freely spins therein until it strikes another side wall 27, 28 of the channel 26, whereupon the spin is either re-activated in the same direction, or a spin in an opposite direction is imparted thereto, depending upon which wall of the channel is struck and the direction of the previous spin. Various and devious paths of movement of the ornamental float and sudden changes of spin are thus brought into play. One such path is illustrated in Figure 2 by the broken line 90.

It will be noted that by the combination of elements in my invention, an interrelation of eye-appealing and attention-drawing movements has been established which is of particular interest to the onlooker. Thus, while his gaze is soothed by the restful miniature landscape with actual vegetation growing thereon, and the quiet, steady movement of the waterwheel turning in constant rhythm before his gaze, which constant rhythm may itself be rendered attention-compelling by the equal and opposite motion of the vertical waterwheels and the steady motion of the horizontal rotor, all bathed in the soft glow of the lighting 56, his attention is constantly being drawn from the restful background to the forever unpredictable movements of the fish which are stirred into alternative actions of swimming against the current or being bodily carried with the current, and the interplay of their movements with the equally unpredictable and devious gyrations and paths of movement of the ornamental floats. Not only so, but the sharp variations of movement of the ornamental floats are accentuated as they come in contact with the guard rail 79 and are restricted in their passage through the channel 26 by the presence therein of the steadily moving waterwheel 70 and the resulting restrictions of the channel available to the spinning ornamental float 65. Not only so, but the fish 89 themselves must negotiate the passage beneath or about the waterwheel 70 when they are either carried by the current through that portion of the channel, or choose to swim therethrough. Should the continuous study of the interplay of motions begin to tire the onlooker, he need merely rest his gaze upon the steadily moving waterwheels and rotor, and the substantially static and scenic landscape. Thus, the beholder may find himself substantially entranced for very long periods of time, shifting his gaze from the quiet, restful scene to the dynamic and unpredictable movements taking place in the channel 26, with the substantially steady movement of the waterwheels and rotor tending to bridge the emotional effect between the quiet of the landscape and the action within the channel.

Not only does the propeller 43 serve to impart current to the channel 26 and bring about an aspiration of air into the water 48, but it also forms an integral part of a water-cleaning method which is available for use in the channel 26. Because of the use of said channel for holding water 48 within which is contained live fish 89, waste matter accumulates and must be cleaned from the channel. This may be done by the simple expedient of opening the cock 40 and draining the dirty water from the channel and replacing it with fresh water. An even simpler method, however, and one which can be achieved in a space of but seconds, while at the same time enabling the same water to be reused, is to lower into the channel a net 91 having sides 92 of substantially the same size and configuration as the interior periphery of the channel 26. Indeed, the side edges 93 of the net 91 may be spaced a distance greater than the distance between the side walls 27 and 28, and the net 91 may then be tilted about its vertical axis until its side edges 93 bear against the side walls 27 and 28. When the propeller 43 is actuated, the current 94 will force the water 48 through the net until it has completed one circuit through the channel 26. In the course of that circuit,

the waste material carried by the water 48 will have been collected by the net 91, and the net may then be removed and cleaned. Inasmuch as the fish 89 tend to swim against the current, in most cases they will not be caught in the net 91. Even if they do swim into contact with the net, however, they need not be removed with the net, for a simple backward movement of the net or a pivoting of the net about its side edges 93 will free the fish 89 therefrom. It will thus be seen that by the use of the propeller 43, the water 48 may be cleaned of waste matter in one complete circuit through the channel 26, while the water itself becomes refreshed by the aspiration of air thereinto.

The growing vegetation 88 may be watered in any desired manner, as by sprinkling or otherwise, and periodically the cock 36 may be opened to drain off water which has seeped through the soil-like substance 81 and accumulated at the bottom of the tray. While fish are kept in the channel 26, the propeller 43 may be actuated if desired at periodic intervals, thereby further varying the demands on the fish, and giving them a rest from the movement experienced during the motion of the water. In effect, the stopping of the propeller 43 will be found to be similar to that of fish swimming from mid-stream to a quiet pool along one side of a channel. Thus, the display device may be used indefinitely. Not only so, but its appearance may be varied considerably without departure from its basic elements, by the substitution of other ornamentation or the mounting of a tree such for instance as a Christmas tree on the island or land regions, and by the substitution of a tree lighting system as illustrated in Figure 9 for a lighting system similar to that illustrated in Figure 1. By so doing the same display device may be used in a number of different ways so as to impart variety of appearance while maintaining the same fundamental attraction.

I am aware that the invention may be embodied in other specific forms without departing from the spirit or essential attributes thereof, and I therefore desire the present embodiments to be considered in all respects as illustrative and not restrictive, reference being had to the appended claims rather than to the foregoing description to indicate the scope of the invention.

Having thus described my invention, what I claim as new and desire to secure by Letters Patent is:

1. In combination, an aquarium comprising a container in the form of a continuous channel; power operated current-producing means in said channel and adapted to impel a flow of water substantially along the course of said channel and in a manner to aspirate air thereinto.

2. In combination, an aquarium comprising a container in the form of a continuous channel; power operated current-producing means in said channel and adapted to impel a flow of water substantially along the course of said channel and in a manner to aspirate air thereinto; said channel having a drainage system.

3. In combination, an aquarium comprising a container in the form of a continuous channel; power operated current-producing means in said channel and adapted to impel a flow of water substantially along the course of said channel and in a manner to aspirate air thereinto; a movable display device mounted on said aquarium; means for deriving motion from said flow of water and transmitting said motion to said display device.

4. In combination, an aquarium comprising a container in the form of a continuous channel; power operated current-producing means in said channel and adapted to impel a flow of water substantially along the course of said channel and in a manner to aspirate air thereinto; a water-wheel mounted on said aquarium and having a substantially horizontal axis and blades disposed thereabout, the path of rotation of said blades intercepting the course of said channel.

5. In combination, an aquarium comprising a container in the form of a continuous channel; power operated

current-producing means in said channel and adapted to impel a flow of water substantially along the course of said channel and in a manner to aspirate air thereto; a water-wheel mounted on said aquarium and having a substantially horizontal axis and blades disposed thereabout, the path of rotation of said blades intercepting the course of said channel; another water-wheel mounted on said aquarium and having a substantially horizontal axis and blades disposed thereabout, the path of rotation of said last-mentioned blades intercepting the course of said channel but being disposed in a portion of said channel wherein the direction of flow with respect to said aquarium is substantially opposite to the direction of flow at said portion of said channel where said first-mentioned water-wheel is disposed.

6. In combination, an aquarium comprising a container in the form of a continuous channel; power operated current-producing means in said channel and adapted to impel a flow of water substantially along the course of said channel and in a manner to aspirate air thereto; a movable display device mounted on said aquarium; means for deriving motion from said flow of water and transmitting said motion to said display device; a water-wheel mounted on said aquarium and having a substantially horizontal axis and blades disposed thereabout, the path of rotation of said blades intercepting the course of said channel; another water-wheel mounted on said aquarium and having a substantially horizontal axis and blades disposed thereabout, the path of rotation of said last-mentioned blades intercepting the course of said channel but being disposed in a portion of said channel wherein the direction of flow with respect to said aquarium is substantially opposite to the direction of flow at said portion of said channel where said first-mentioned water-wheel is disposed.

7. In combination, an aquarium comprising a container in the form of a continuous channel; power operated current-producing means in said channel and adapted to impel a flow of water substantially along the course of said channel and in a manner to aspirate air thereto; a float device having a vertical axis, peripheral projections disposed about said vertical axis, means to maintain said axis in a substantially vertical condition when said float is freely supported by its own buoyancy in said water.

8. In combination, an aquarium comprising a container in the form of a continuous channel; power operated current-producing means in said channel and adapted to impel a flow of water substantially along the course of said channel and in a manner to aspirate air thereto; a movable display device mounted on said aquarium; means for deriving motion from said flow of water and transmitting said motion to said display device; a float device having a vertical axis, peripheral projections disposed about said vertical axis, means to maintain said axis in a substantially vertical condition when said float is freely supported by its own buoyancy in said water.

9. In combination, an aquarium comprising a container in the form of a continuous channel; power operated current-producing means in said channel and adapted to impel a flow of water substantially along the course of said channel and in a manner to aspirate air thereto; a water-wheel mounted on said aquarium and having a substantially horizontal axis and blades disposed thereabout, the path of rotation of said blades intercepting the course of said channel; a float device having a vertical axis, peripheral projections disposed about said vertical axis, means to maintain said axis in a substantially vertical condition when said float is freely supported by its own buoyancy in said water.

10. In combination, an aquarium comprising a container in the form of a continuous channel; power operated current-producing means in said channel and adapted to impel a flow of water substantially along the course of said channel and in a manner to aspirate air thereto; a moveable display device mounted on said

aquarium; means for deriving motion from said flow of water and transmitting said motion to said display device; a water-wheel mounted on said aquarium and having a substantially horizontal axis and blades disposed thereabout, the path of rotation of said blades intercepting the course of said channel; a float device having a vertical axis, peripheral projections disposed about said vertical axis, means to maintain said axis in a substantially vertical condition when said float is freely supported by its own buoyancy in said water.

11. In combination, an aquarium comprising a container in the form of a continuous channel; power operated current-producing means in said channel and adapted to impel a flow of water substantially along the course of said channel and in a manner to aspirate air thereto; a water-wheel mounted on said aquarium and having a substantially horizontal axis and blades disposed thereabout, the path of rotation of said blades intercepting the course of said channel; another water-wheel mounted on said aquarium and having a substantially horizontal axis and blades disposed thereabout, the path of rotation of said last-mentioned blades intercepting the course of said channel, but being disposed in a portion of said channel wherein the direction of flow with respect to said aquarium is substantially opposite to the direction of flow at said portion of said channel where said first-mentioned water-wheel is disposed; a float device having a vertical axis, means to maintain said axis in a substantially vertical condition when said float is freely supported by its own buoyancy in said water.

12. In combination, an aquarium comprising a container in the form of a continuous channel; power operated current-producing means in said channel and adapted to impel a flow of water substantially along the course of said channel and in a manner to aspirate air thereto; a moveable display device mounted on said aquarium; means for deriving motion from said flow of water and transmitting said motion to said display device; a water-wheel mounted on said aquarium and having a substantially horizontal axis and blades disposed thereabout, the path of rotation of said blades intercepting the course of said channel; another water-wheel mounted on said aquarium and having a substantially horizontal axis and blades disposed thereabout, the path of rotation of said last-mentioned blades intercepting the course of said channel, but being disposed in a portion of said channel wherein the direction of flow with respect to said aquarium is substantially opposite to the direction of flow at said portion of said channel where said first-mentioned water-wheel is disposed; a float device having a vertical axis, peripheral projections disposed about said vertical axis, means to maintain said axis in a substantially vertical condition when said float is freely supported by its own buoyancy in said water.

13. In combination, an aquarium comprising a container in the form of a continuous channel; power operated current-producing means in said channel and adapted to impel a flow of water substantially along the course of said channel and in a manner to aspirate air thereto; anchor means on said aquarium adapted to secure in substantially upright condition a tree-trunk whose base is severed.

14. In combination, an aquarium comprising a container in the form of a continuous channel; power operated current-producing means in said channel and adapted to impel a flow of water substantially along the course of said channel and in a manner to aspirate air thereto; a conduit extending through said aquarium and adapted to carry electrical wiring from the exterior to a display portion carried by said aquarium.

15. In combination, an aquarium comprising a container in the form of a continuous channel; power operated current-producing means in said channel and

adapted to impel a flow of water substantially along the course of said channel and in a manner to aspirate air thereto; anchor means on said aquarium adapted to secure in substantially upright condition a tree-trunk whose base is severed; a conduit extending through said aquarium and adapted to carry electrical wiring from the exterior to a display portion carried by said aquarium.

16. In combination, an aquarium comprising a container in the form of a continuous channel; power operated current-producing means in said channel and adapted to impel a flow of water substantially along the course of said channel and in a manner to aspirate air thereto; a portion of said aquarium being adapted to hold a soil-like substance and vegetation; drainage means for said last-mentioned portion; anchor means on said aquarium adapted to secure in substantially upright condition a tree-trunk whose base is severed, and which base is disposed substantially in said soil-like substance.

17. In combination, an aquarium comprising a container in the form of a continuous channel; power operated current-producing means in said channel and adapted to impel a flow of water substantially along the course of said channel and in a manner to aspirate air thereto; a moveable display device mounted on said aquarium; means for deriving motion from said flow of water and transmitting said motion to said display device; anchor means on said aquarium adapted to secure in substantially upright condition a tree-trunk whose base is severed.

18. In combination, an aquarium comprising a container in the form of a continuous channel; power operated current-producing means in said channel and adapted to impel a flow of water substantially along the course of said channel and in a manner to aspirate air thereto; a water-wheel mounted on said aquarium and having a substantially horizontal axis and blades disposed thereabout, the path of rotation of said blades intercepting the course of said channel; anchor means on said aquarium adapted to secure in substantially upright condition a tree-trunk whose base is severed.

19. In combination, an aquarium comprising a container in the form of a continuous channel; power operated current-producing means in said channel and adapted to impel a flow of water substantially along the course of said channel and in a manner to aspirate air thereto; a float device having a vertical axis, peripheral projections disposed about said vertical axis, means to maintain said axis in a substantially vertical condition when

said float is freely supported by its own buoyancy in said water; anchor means on said aquarium adapted to secure in substantially upright condition a tree-trunk whose base is severed.

5. 20. In combination, an aquarium comprising a container in the form of a continuous channel; power operated current-producing means in said channel and adapted to impel a flow of water substantially along the course of said channel and in a manner to aspirate air thereto; 10 a moveable display device mounted on said aquarium; means for deriving motion from said flow of water and transmitting said motion to said display device; a water-wheel mounted on said aquarium and having a substantially horizontal axis and blades disposed thereabout, the path of rotation of said blades intercepting the course of said channel; another water-wheel mounted on said aquarium and having a substantially horizontal axis and blades disposed thereabout, the path of rotation of said last-mentioned blades intercepting the course of said channel, but being disposed in a portion of said channel wherein the direction of flow with respect to said aquarium is substantially opposite to the direction of flow at said portion of said channel where said first-mentioned water-wheel is disposed; a float device having a vertical axis, peripheral projections disposed about said vertical axis, means to maintain said axis in a substantially vertical condition when said float is freely supported by its own buoyancy in said water; a portion of said aquarium being adapted to hold a soil-like substance and vegetation; anchor means on said aquarium adapted to secure in substantially upright condition a tree-trunk whose base is severed, and which base is disposed substantially in said soil-like substance.
